APPARATUS FOR PRINTING SPACED TEXT PORTIONS ADJACENT EACH OTHER**Wilhelm Ritterfeld, Berlin-Dahlem, and Gerhard Ritterfeld, Berlin-Grunewald, Germany****Application April 27, 1955, Serial No. 509,264****Claims priority, application Germany April 28, 1954****10 Claims. (Cl. 101—132.5)**

The present invention relates to a method and apparatus for printing spaced text portions adjacent each other on a copy sheet, and more particularly to an apparatus including a plurality of cam means for actuating a pressure roller to engage a printing roller only when desired text portions pass through a printing line defined by the printing roller and a pressure roller.

In known printing apparatus, and more particularly in duplicating machines for printing from mirror script master sheets, it is known to print from the master sheet a head portion and one or several consecutive lines adjacent the head portion. However, the devices of the known art have the disadvantage that it is impossible to print a plurality of spaced and variable text portions adjacent each other on a copy sheet.

It is the object of the present invention to overcome disadvantages of the known art, and to provide an apparatus and method for printing a plurality of spaced text portions adjacent each other on a copy sheet.

It is another object of the present invention to provide for a variation of the number of lines printed from each text portion.

It is a further object of the present invention to provide for an adjustment of the apparatus permitting selecting of desired portions of the text which are to be printed adjacent each other on copy sheets.

With these objects in view the present invention mainly consists in a method for printing a plurality of text portions spaced on a printing form from each other in one direction comprising the steps of moving a copy sheet and the printing form in contact with each other in the direction through a printing station while a first portion of the text passes through the printing station; moving the copy sheet and the printing form out of contact while the text moves relative to the printing station and to the copy sheet until a second portion of the text arrives at the printing station; moving the copy sheet and the printing form into contact with each other at the printing station while the second portion of the text passes through the printing station, and repeating the steps until a selected number of text portions is printed adjacent each other on the copy sheet.

The apparatus according to the present invention mainly comprises a rotary printing roller adapted to support a printing form having a text thereon having lines extending in axial direction of the printing roller, the printing roller being adapted to move the printing form through a printing line; a pressure roller cooperating with the printing roller at the printing line; movable supporting means supporting the pressure roller for movement between an operative position engaging the printing roller and an inoperative position spaced from the printing roller, the rollers being adapted to grip a supplied copy sheet along the printing line and to transport the same in printing engagement with the printing roller only when the pressure roller is in the operative position; holding means for holding the copy sheet stationary when the pressure roller is in the inoperative position; and a plurality of

2

shifting means connected to the printing roller and actuated by rotation thereof, the shifting means engaging the movable supporting means and moving the same and therewith the pressure roller repeatedly during each revolution of the duplicating roller from the inoperative position to the operative position for printing spaced portions of the text on the printing roller adjacent each other on a copy sheet.

The shifting means are preferably cam means which include a plurality of cam discs having cam tracks cooperating with cam follower rollers on the supporting means of the pressure roller. The cam means are shiftable so that the number of cam discs cooperating with the respective cam follower can be adjusted. Thereby the effective length of the cam track is varied whereby the number of lines printed from the respective text portion is adjusted.

The cam means of the cam device are turnable relative to each other for selecting desired spaced portions of the printed text for adjacent print on the copy sheet.

The printing form, or master sheet, which is attached to the printing roller is arranged with the lines thereof extending in axial direction of the printing roller. By shifting the pressure roller into engagement with the printing form whenever a desired portion of the text passes through the printing line, and by holding the copy sheet stationary while undesired portions of the printed text pass through the printing line, it is possible to print desired portions of the text adjacent each other.

In the event that it is desired to have a space between portions printed on the copy sheet, the copy sheet is transported while the printing roller and pressure roller are spaced from each other so that no printing takes place.

According to the present invention it is possible to print a head portion of the printed text, whose position can be adjusted, and in addition thereto a plurality of selected spaced text portions including a variable number of lines adjacent each other on the copy sheet.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

Fig. 1 is a side view of an apparatus according to the present invention;

Fig. 2 is a sectional view taken on line A—B in Fig. 1;

Fig. 3 is a side view of a cam device used in the arrangement of Fig. 1;

Fig. 4 is a side view, partly in section taken on line C—D in Fig. 5, of a cam shifting device;

Fig. 5 is an axial sectional view illustrating a cam device according to the present invention on an enlarged scale;

Fig. 6 is a longitudinal sectional view of a master sheet;

Figs. 7 and 8 are longitudinal sectional views of copy sheets printed in accordance with the present invention; and

Fig. 9 is a cross-sectional view taken on line E—F in Fig. 5 illustrating the operating means for the cam shifting device.

Referring now to the drawings, and more particularly to Fig. 1, on a printing drum 1 a master sheet 2 is held by a clamping device 3. A pressure roller 5 cooperates with the printing drum 1, which is a duplicating roller according to the preferred embodiment of the present invention. The pressure roller 5 is pivotable about a shaft 4 and mounted on movable supporting means 20, 21, 22, 23 permitting to move the pressure roller between an

operative position engaging the duplicating roller 1 along a printing line located in the printing plane 28 and an inoperative position spaced therefrom. A copy sheet 24 is fed by the transporting rollers 26, 27 constituting supply means to the printing line where it is gripped by the rollers 1 and 5 for printing when the roller 5 is in its operative position. When the roller 5 is in its inoperative position, the holding means 125 maintains the copy sheet stationary.

The movable supporting means of the pressure roller 5 are shifted by operating levers 16, 17 and 18 provided with cam follower rollers 16¹, 17¹ and 18¹ and mounted on a common shaft 19 which is turnably mounted on stationary supporting means such as the casing of the apparatus.

The shifting of the pressure roller 5 is controlled by a cam device which includes the following elements: a head cam means 7 which is associated with the head portion of the text on the master sheet 2, a set of cam discs 8¹, 8², 8³ having cam track portions for extending the length of the cam track of the head cam means, cam discs 9¹, 9², 9³ and 9⁴ having various effective cam track lengths for printing variable head portions of the master sheet, and cam discs 10¹, 10² and 10³ for printing one, two or three lines of the text of the master sheets. The cam discs, excepting cam 7, are adjustable in axial direction and can be also turned relative to each other as will be described hereinafter in more detail. In order to be able to print the master sheet in its entirety, a duplicating cam 11 is connected to the set of cams 8 by means of the bolt 12. The cam units 8¹, 8², 8³, 11 is shiftable in axial direction but adjustment to a desired length of the printed head portion must be carried out in the work shop.

In order to obtain a synchronous run of the cam device with the printing drum 1, the shaft 6 which supports the cam device, is driven through gears 14 and 15 from the gear 13 which is connected for rotation to the printing drum 1.

The cam means 7, 8¹ to 8³; 9¹ to 9⁴; and 10¹ to 10³ and 11; cooperate with the operating levers 16, 17 and 18 through cam follower rollers 16¹, 17¹ and 18¹, respectively. In accordance with the effective length of the cam track engaging the cam follower rollers, the shaft 19 and thereby the supporting means 20 of the pressure roller 5 are shifted.

When, for instance, the set of cams 9¹, 9², 9³ and 9⁴ is shifted in axial direction relative to the cam follower roller 17¹, the latter first cooperates only with the cam disc 9¹, then with cam discs 9¹ and 9², etc. so that the time period for which the pressure roller 5 is shifted into its operative position is adjusted since the cam track formed by the cam tracks of cam discs 9¹ and 9² is longer than the cam track of cam disc 9¹ alone, as can be clearly seen in Fig. 3. The movement of the operating levers 16, 17 and 18 is transmitted through the lever 20, and the toggle levers 21, 22 and 23 to the pressure roller 5.

The cam discs 9¹ to 9⁴ which are associated with the intermediate variable head portion of the master sheet, and the cam discs 10¹ to 10³ which are associated with the lines of the text of the master sheet are turned by means of a ratchet device which is operated by levers 33, or by levers 34, 35 and 36 which stepwise turn the cams 10¹ to 10³ and 9¹ to 9⁴. Any one of the levers 34, 35 and 36 can be selectively actuated so that the cam tracks of the cam means jump one, two or three lines, as desired.

The arrangement of the cam device is illustrated in Fig. 5 on an enlarged scale. Referring now to Fig. 5, the cam shaft 6 is driven through the gears 13, 14 and 15 from the shaft 1a of the printing roller 1. The head cam 7 is secured to the shaft 6 by means of the carrier 38 which is fixedly connected to shaft 6 by a key 39 and a pin 40. The set of cam discs 8¹ to 8³ is connected

by means of a bolt 12 to an axially movable carrier means 41 including a hub portion and a flange portion. The carrier 41 is mounted on the shaft 6 non-rotatable and movable in axial direction by means of key 42. Since the set of cams 8¹ to 8³ is movable with the carrier 41 in axial direction, the cam tracks of the cams 8¹ alone, 8¹ and 8², or 8¹, 8² and 8³, respectively, can be placed into position for actuating the cam follower roller 16¹ whereby the length of time during which the pressure roller 5 engages the printing roller 1 is adjusted. Further axial shifting of the unit brings the duplicating cam 11 into engagement with the cam follower roller 16¹ for printing the entire text of the master sheet 2.

A ratchet carrier means 43 is fixedly connected to the shaft 6. A locking pawl 30 and a shifting pawl 29 are turnably mounted on a pin 44 on the ratchet carrier 43 and are under the action of springs 45 and 46, respectively. The locking pawl 30 engages the ratchet wheel 47 which is mounted together with the chain wheel 48 on the carrier means 37 which includes a hub portion and a flange portion. The carrier means 37 is turnably mounted on the shaft 6 and is urged by a spring means 59 against the locking pawl 30. A support 56 is mounted on the carrier means 37 for axial movement by means of a key 49 and carries the cam discs 9¹ to 9⁴ which are connected thereto by a bolt 12a. When the support 56 is shifted in axial direction on the carrier means 37, the cams 9¹ to 9⁴ are selectively brought into engagement with the cam follower roller 17¹ on the operating lever 17. By operation of the ratchet device 29, 30 and 47, it is possible to adjust the position of the cams 9¹ to 9⁴ relative to cam means 8¹ to 11 in peripheral direction so that the same engage earlier or later the cam follower roller 17¹ of the operating lever 17 during rotation of the cam device.

The member 15 is fixed on the shaft 6 and carries on bolt 51 the locking pawl 32 and the shifting pawl 31 which are turned by springs 52 and 53, respectively, into engagement with the ratchet wheel 54 which is secured to the carrier means 37a together with the chain wheel 55.

The carrier means 37a is turnably mounted on the shaft 6 and is urged by the spring means 56 against the locking pawl 32. The support 57 is mounted on the carrier means 37a shiftable in axial direction but non-rotatable. A key 58 connects the members 37a and 57. The cam discs 10¹ to 10³ which are associated with the lines of the master sheet are secured to the flange portion of the support 57 by a bolt 12b. Since carrier 37a is shiftable in axial direction on shaft 6, groups of the cams 10¹ to 10³ can be selectively brought into engagement with the cam follower 18¹ on the operating lever 18. By operation of the ratchet device 31, 32, 54 it is possible to adjust the relative angular position on shaft 6 the moment in which the cams 10¹ to 10³ are effective on the cam follower roller 18¹ and actuate the pressure roller 5.

The chain wheels 48 and 55 serve for winding up the ratchet devices 29, 30, 47 and 31, 32, 54, respectively, for returning the set of cams 9¹ to 9⁴, and 10¹ to 10³, to initial positions. All cams can be adjusted in peripheral direction by loosening the bolts 12, 12a and 12b which pass through circumferential slots in the cams. For the sake of clarity, the arrangement illustrated in Fig. 5 is not shown in detail in Fig. 2.

Referring now to Fig. 9, the axial shifting of the set of cams 10¹ to 10³ and of the associated support 57 is carried out by means of the operating rod 61, a slide 63 sliding on the bolt 64 and the triangular lever 65 which is turnable about the bolt 66. The pivotal movement of the lever 65 is transmitted through the link 67 to a lever 68. Lever 68 is mounted on the shaft 69 and has a cylindrical portion 70 provided with a helical groove 71. A fork-shaped lever 72 extends over the portion 70 of the lever 68, and a pin 73, which is fixed to the sleeve

74 of the fork lever 72, engages the helical groove 71. When the lever 68 is pivoted, the fork lever 72 is shifted in axial direction due to the action of the pin 73 in the helical groove 71, and thereby shifts with its pin 75 the support 57 and the cams 10¹ to 10³. The sets of cams 8¹ to 8³, 11 and 9¹ to 9⁴ are shifted in a similar manner in axial direction. The shifted position of the above-described members is illustrated in broken lines in Fig. 9.

The turning of the cam means 10¹ to 10³ in circumferential is carried out by the ratchet device 29, 30 and 54. While the printing roller 1 is at a standstill, the manually operated key 76, turnable about pin 77, is actuated, whereby through the link 78 the lever 33 is turned about pin 66. The roller 33 associated with the same engages the shifting pawl 29 which turns about pin 51 so that its point 79 engages a recess between the teeth of the ratchet wheel 54. Due to the action of the guiding face 80 of the shifting pawl 29 which abuts against a face 81 of the locking pawl 30, the same is lifted out of the region of the teeth of the ratchet wheel 54. Under the action of the spring means 56, the ratchet wheel 54 is pulled together with the next following tooth against the point 79 of the shifting pawl 29. When the key 76 is released, the spring 82 retracts the key 76 and the linkage means 78, 33 into initial position engaging the stop 83. Due to the action of the spring 46, the shifting pawl 29 is disengaged from the ratchet wheel 54 while the spring 45 urges the locking pawl 30 into engagement with the next following tooth of the ratchet wheel 54. During this operation, the ratchet wheel 54 and thereby the line cams 10¹ and 10³ have been shifted one step corresponding to one line spacing in the direction opposite to the direction of rotation indicated by the arrow G.

The above operation can be automatically carried out during each revolution of the printing roller 1 without actuating the key 76.

The hand lever 84 for the automatic shifting of the line cam discs 10¹ to 10³ moves the support 85 which is mounted on pins 64 and 86. At first, only the shifting lever 87 and the roll 34 mounted thereon are moved into the path of the shifting pawl 29 so that the shifting pawl 29 performs one shifting operation, as described above, during one revolution of the printing roller 1. This corresponds only to the action of the cam 10³ on the cam follower roller 18¹. If due to further operation of the rod 61, the cams 10² or 10¹ are brought into engagement with the roller 18¹, the slide 63 turns the lever 89 on the stationary pin 90 by means of pin 88.

Due to this turning of the lever 89, at first the carrier 91 with the associated roller 36 is raised into the path of the shifting pawl 29, so that the shifting pawl 29 shifts twice through the rolls 36 and 34 during one revolution of the printing roller 1. When the slide 63 is further shifted, the lever 89 pivots without causing a change in the position of the roll 36, so that also roll 35 acts on the lever 92.

When the automatic shifting means are disconnected, the levers 91 and 92 are disengaged from the lever 89, and the rolls 35, 36 are moved out of the path of the shifting pawl 29, and together with the lever 87 and the roll 34.

In order to return the line cam means 10¹ to 10³ to its initial positions, the chain wheel 55 is turned through hand wheel 93, chain wheel 94, chain 95 against the action of the spring means 56 in the direction of the arrow G and locked by the locking pawl 30. A dial 96 is connected to the chain wheel 94 for indicating the position of the cams 10¹ to 10³. A similar mechanism is provided for the cams 9¹ to 9⁴ for turning the same so as to adjust the peripheral position of the associated cam tracks relative to the other cam means.

Fig. 6 shows a master sheet having a head portion K, an intermediate head portion WK, a portion Z₂ including a plurality of lines, and the portion Z₁ extending through one line. These portions are to be printed adjacent each other on a copy sheet 24, as shown in Figs. 7 and 8, al-

though they are spaced from each other on the master sheet 2. Fig. 7 shows a head portion K, the intermediate head portion WK and the line portion Z₂ printed adjacent each other. As shown in Fig. 8 by appropriate operation of the cam device, another line Z₁ can be printed adjacent the head portion and the intermediate head portion.

In this manner, it is possible to print from an original master sheet selected portions required for a particular order sheet or accounting operation. Such selected portions appear on the printed copy adjacent each other. It will be understood that this constitutes a great advantage for printing bills and order sheets in industrial plants.

It will be understood that each of the elements described above, or two or more together, may also find a useful application in other types of printing apparatus and methods differing from the types described above.

While the invention has been illustrated and described as embodied in printing apparatus for printing text portions of a master sheet selectively and adjacent each other on a copy sheet, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

35. 1. In a rotary printing device comprising, in combination, a rotary printing roller adapted to support a printing form having a text thereon having lines extending in axial direction of said printing roller, said printing roller being adapted to move the printing form through a printing line; a pressure roller cooperating with said printing line; movable supporting means supporting said pressure roller for movement between an operative position engaging said printing roller and an inoperative position spaced from said printing roller, said rollers being adapted to grip a supplied copy sheet along said printing line and to transport the same in printing engagement with said printing roller only when said pressure roller is in said operative position; holding means for holding the copy sheet stationary when said pressure roller is in said inoperative position; a rotary cam device including a plurality of cam means, said rotary cam device being connected to said printing roller for rotation therewith so as to turn in timed relationship with the text on the same, each of said cam means consecutively engaging said movable supporting means and moving the same and therewith said pressure roller during each revolution of said printing roller from said inoperative position to said operative position for printing spaced portions of the text adjacent each other on a copy sheet, said pressure roller being in said inoperative position thereof when undesired portions of the text move through said printing line, at least one of said cam means including a carrier means, and a plurality of cam discs mounted on said carrier means shiftable in axial direction and having cam tracks corresponding to line portions of said text; and a cam follower roller mounted on said movable supporting means and cooperating with said cam discs, the number of cam discs engaging said cam follower roller during rotation of said cam device being adjustable by shifting said cam discs in axial direction.
- 70 2. In a rotary printing device comprising, in combination, a rotary printing roller adapted to support a printing form having a text thereon having lines extending in axial direction of said printing roller, said printing roller being adapted to move the printing form through

a printing line; a pressure roller cooperating with said printing roller at said printing line; movable supporting means supporting said pressure roller for movement between an operative position engaging said printing roller and an inoperative position spaced from said printing roller, said rollers being adapted to grip a supplied copy sheet along said printing line and to transport the same in printing engagement with said printing roller only when said pressure roller is in said operative position; holding means for holding the copy sheet stationary when said pressure roller is in said inoperative position; a shaft connected to said printing roller for rotation therewith so as to turn in timed relationship with the text on the same; a rotary cam device including a plurality of cam means and being mounted on said shaft, at least one of said cam means including a carrier means turnably mounted on said shaft, a movable support mounted on said carrier means shiftable in axial direction and non-rotatable relative thereto, and a plurality of cam discs connected to said support for rotation therewith, each cam disc having a cam track corresponding to a line portion of said text; and a plurality of cam follower rollers mounted on said movable supporting means and cooperating with said cam means, one of said cam follower rollers cooperating with said cam tracks of said cam discs, the number of cam discs engaging said cam follower roller during rotation of said cam device being adjustable by shifting said movable support and said cam discs in axial direction.

3. In a rotary printing device comprising, in combination, a rotary printing roller adapted to support a printing form having a text thereon having lines extending in axial direction of said printing roller, said printing roller being adapted to move the printing form through a printing line; a pressure roller cooperating with said printing roller at said printing line; movable supporting means supporting said pressure roller for movement between an operative position engaging said printing roller and an inoperative position spaced from said printing roller, said rollers being adapted to grip a supplied copy sheet along said printing line and to transport the same in printing engagement with said printing roller only when said pressure roller is in said operative position; holding means for holding the copy sheet stationary when said pressure roller is in said inoperative position; a plurality of cam follower means connected to said movable supporting means; a shaft connected to said printing roller for rotation therewith; and a rotary cam device including a plurality of cam means and being mounted on said shaft, each of said cam means including a plurality of cam discs having cam tracks corresponding to portions of said text, each of said cam means being shiftable in axial direction between a plurality of positions in which a different number of said cam discs cooperate with the associated cam follower roller, at least one of said cam means being turnable on said shaft for adjusting the position of said cam tracks with respect to said cam follower means.

4. In a rotary printing device comprising, in combination, a rotary printing roller adapted to support a printing form having a text thereon having lines extending in axial direction of said printing roller, said printing roller being adapted to move the printing form through a printing line; a pressure roller cooperating with said printing roller at said printing line; movable supporting means supporting said pressure roller for movement between an operative position engaging said printing roller and an inoperative position spaced from said printing roller, said rollers being adapted to grip a supplied copy sheet along said printing line and to transport the same in printing engagement with said printing roller only when said pressure roller is in said operative position; holding means for holding the copy sheet stationary when said pressure roller is in said inoperative position; a plurality of cam follower means connected to said movable supporting means; a shaft connected to said printing roller for rotation therewith; and a rotary cam device including a plurality of cam means and being

mounted on said shaft, each of said cam means including a plurality of cam discs having cam tracks corresponding to portions of said text, each of said cam means being shiftable in axial direction between a plurality of positions in which a different number of said cam discs cooperate with the associated cam follower roller, at least one of said cam means being turnable on said shaft for adjusting the position of said cam tracks with respect to said cam follower means.

- 10 5. In a rotary printing device comprising, in combination, a rotary printing roller adapted to support a printing form having a text thereon having lines extending in axial direction of said printing roller, said printing roller being adapted to move the printing form through a printing line; a pressure roller cooperating with said printing roller at said printing line; movable supporting means supporting said pressure roller for movement between an operative position engaging said printing roller and an inoperative position spaced from said printing roller, said rollers being adapted to grip a supplied copy sheet along said printing line and to transport the same in printing engagement with said printing roller only when said pressure roller is in said operative position; holding means for holding the copy sheet stationary when said pressure roller is in said inoperative position; a plurality of cam follower means connected to said movable supporting means; a shaft connected to said printing roller for rotation therewith; a rotary cam device including a plurality of cam means and being mounted on said shaft, each of said cam means including a plurality of cam discs having cam tracks corresponding to portions of said text, each of said cam means being shiftable in axial direction between a plurality of positions in which a different number of said cam discs cooperate with the associated cam follower roller, at least one of said cam means being turnable on said shaft for adjusting the position of said cam tracks with respect to said cam follower means; and means for turning said at least one cam means on said shaft.
- 15 30 6. In a rotary printing device comprising, in combination, a rotary printing roller adapted to support a printing form having a text thereon having lines extending in axial direction of said printing roller, said printing roller being adapted to move the printing form through a printing line; a pressure roller cooperating with said printing roller at said printing line; movable supporting means supporting said pressure roller for movement between an operative position engaging said printing roller and an inoperative position spaced from said printing roller, said rollers being adapted to grip a supplied copy sheet along said printing line and to transport the same in printing engagement with said printing roller only when said pressure roller is in said operative position; holding means for holding the copy sheet stationary when said pressure roller is in said inoperative position; a shaft connected to said printing roller for rotation therewith so as to turn in timed relationship with the text on the same; a rotary cam device including a plurality of cam means and being mounted on said shaft, at least one of said cam means including a carrier means turnably mounted on said shaft, a movable support mounted on said carrier means shiftable in axial direction and non-rotatable relative thereto, and a plurality of cam discs connected to said support for rotation therewith, each cam disc having a cam track corresponding to a line portion of said text, and another of said cam means being fixedly connected to said cam shaft for rotation therewith for printing a head portion of the text; and a plurality of cam follower rollers mounted on said movable supporting means and cooperating with said cam means, one of said cam follower rollers cooperating with said cam tracks of said cam discs, the number of cam discs engaging said cam follower roller during rotation of said cam device being adjustable by shifting said movable support and said cam discs in axial direction.
- 20 35 40 45 50 55 60 65 70 75

7. An arrangement as claimed in claim 6 wherein one of said cam means includes a cam disc having a cam track shaped in such manner as to actuate said movable supporting means to move said pressure roller into its operative position while the entire text passes through said printing line.

8. In a rotary printing device comprising, in combination, a rotary printing roller adapted to support a printing form having a text thereon having lines extending in axial direction of said printing roller, said printing roller being adapted to move the printing form through a printing line; a pressure roller cooperating with said printing roller at said printing line; movable supporting means supporting said pressure roller for movement between an operative position engaging said printing roller and an inoperative position spaced from said printing roller, said rollers being adapted to grip a supplied copy sheet along said printing line and to transport the same in printing engagement with said printing roller only when said pressure roller is in said operative position; holding means for holding the copy sheet stationary when said pressure roller is in said inoperative position; and a rotary cam device driven from said printing roller so as to turn in timed relationship with the text on the same, said cam device including at least a first cam means associated with a head portion of said text, a second cam means associated with an intermediate head portion of said text, and a third cam means associated with line portions of said text, each of said cam means consecutively engaging said movable supporting means and moving the same and therewith said pressure roller during each revolution of said printing roller from said inoperative position to said operative position for printing spaced portions of the text adjacent each other on a copy sheet, said pressure roller being in said inoperative position thereof when undesired portions of the text move through said printing line.

9. In a rotary printing device comprising, in combination, a rotary printing roller adapted to support a printing form having a text thereon having lines extending in axial direction of said printing roller, said printing roller being adapted to move the printing form through a printing line; a pressure roller cooperating with said printing roller at said printing line; movable supporting means supporting said pressure roller for movement between an operative position engaging said printing roller and an inoperative position spaced from said printing roller, said rollers being adapted to grip a supplied copy sheet along said printing line and to transport the same in printing engagement with said printing roller only when said pressure roller is in said operative position; holding means for holding the copy sheet stationary when said pressure roller is in said inoperative position; and a rotary cam device driven from said printing roller so as to turn in timed relationship with the text on the same, said cam device including at least a first cam means associated with a head portion of said text, a second cam means associated with an intermediate head portion of said text, said second cam means including a plurality of cam discs having cam

tracks together forming the cam track of said second cam means, said cam discs being turnable relative to each other between a plurality of positions for varying the effective length of the cam track of said second cam means, and a third cam means associated with line portions of said text, said third cam means including a plurality of cam discs having cam tracks together forming the cam track of the third cam means, said cam discs being turnable between a plurality of positions for varying the effective length of the cam track of said third cam means, each of said cam means consecutively engaging said movable supporting means and moving the same and therewith said pressure roller during each revolution of said printing roller from said inoperative position to said operative position for printing spaced portions of the text adjacent each other on a copy sheet, said pressure roller being in said inoperative position thereof when undesired portions of the text move through said printing line.

10. In a rotary printing device comprising, in combination, a rotary printing roller adapted to support a printing form having a text thereon having lines extending in axial direction of said printing roller, said printing roller being adapted to move the printing form through a printing line; a pressure roller cooperating with said printing roller at said printing line; movable supporting means supporting said pressure roller for movement between an operative position engaging said printing roller and an inoperative position spaced from said printing roller, said rollers being adapted to grip a supplied copy sheet along said printing line and to transport the same in printing engagement with said printing roller only when said pressure roller is in said operative position; holding means for holding the copy sheet stationary when said pressure roller is in said inoperative position; a plurality of cam follower rollers mounted on said movable supporting means; a shaft connected to said printing roller for rotation therewith; a rotary cam device including a plurality of cam means and being mounted on said shaft for rotation therewith, each of said cam means cooperating with one of said cam follower rollers, at least one of said cam means including a plurality of cam discs and being movable on said shaft in axial direction between a plurality of positions in which a different number of said cam discs cooperates with the associated cam follower roller, said cam discs having adjacent cam tracks together forming the cam track of said at least one cam means so that the length of said last-mentioned cam track cooperating with the associated cam follower roller is varied by axial shifting of said at least one cam means; and means for turning said cam means relative to each other between a plurality of adjusted positions for selecting text portions.
